UNITED STATES PATENT OFFICE.

FRANZ J. WOOD, OF DES MOINES, IOWA.

MOLDING MACHINE.

Application filed January 13, 1921. Serial No. 437,044.

To all whom it may concern:

Be it known that I, FRANZ J. WOOD, a citizen of the United States, and resident of Des Moines, in the county of Polk and State of Iowa, have invented a certain new and useful Improved Molding Machine, of which the following is a specification.

This invention relates to an improved machine for forming sand molds of that class of machines designed to handle the flask and pattern for the purpose of mechanically packing or pressing the molding material within the flask and around the pattern, and particularly pertains to certain improvements on the device illustrated and described in my copending application filed January 2, 1920, Serial Number 349,039, on a molding machine.

The object of my invention is to provide, in a molding machine, new and improved means for controlling the sand and packing devices, and also the mechanism for moving the patterns.

A further object is to provide improved means for locking and unlocking the flask in position on the flask supporting frame.

A further object is to provide in such a machine mechanism operated by compressed air, whereby a platform supporting molding material in a proper flask may be forced upward with a steady, uniform, powerful and increasing pressure against the sand within the flask and surrounding the pattern supported above the said platform.

Still a further object is to provide such a machine in which the air may be adjustably controlled to operate mechanism for drawing the sand away from the pattern in a slow and steady initial movement.

These and other objects, which need not be mentioned in detail, will be apparent to those skilled in the art.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a side elevation of my improved molding machine.

Figure 2 is a plan view of the same.

Figure 3 is a horizontal sectional view, taken on the line 3-3 of Figure 1, showing the mold supporting platform swung to a position outside of the frame.

Figure 4 is a detail sectional view, taken on the line 4-4 of Figure 1, showing in dotted lines the manner in which the flasks are applied thereto.

Figure 5 is a detail view, showing the locking mechanism for securing the pattern supporting frame against rotation.

Figure 6 is a back end elevation, showing the mold supporting platform in its elevated position and the manner in which the link devices for elevating said platform operate, the operating cylinder being removed.

Figure 7 is a central sectional view, taken through the air cylinder and the valve mechanism for controlling the same; and

Figure 8 is a detail sectional view showing the controlling valve in another position from that in which it is shown in Figure 7.

My improved molding machine comprises a base 10 mounted upon suitable wheels 11, which are secured to one end of the base member 10 by means of suitable axles, while the opposite end of the base member is provided with a single wheel, as clearly shown in Figure 2. By mounting the base upon three wheels, as illustrated, a very stable support is provided for the base member, all tilting and rocking movement of the machine being eliminated by the three-point support.

Secured to each end of the base 10 are upright members 12. These uprights 12 are secured in position by means of bolts 14, and have pivotally mounted in their upright ends a frame member 13, which I shall term the pattern supporting frame. This pattern supporting frame is provided at each end with pivots 15, so arranged that the said frame may be rotated with either side uppermost.

The frame 13 is designed to have its faces held in horizontal position by means of a latch device 16 which is mounted in a boss 17 of one of the members 12. This boss is formed with a large opening, which is designed to receive a spring 18, one end of which rests against the boss while the opposite end rests against a shoulder of the latch 16. The outer end of the latch member 16 is pivoted to a lever 19, one end of which is provided with a handle while the opposite end is pivoted to the member 12 by means of a bolt 20. The inner or latch end of the member 16 is designed to enter a notch 21 in the frame 13, and is held in position by means of the spring 18.

For supporting the flask in position on either or both of said faces of the member 13 I have provided at each end of said member and in each of the faces, a post 22 of a length slightly greater than the depth of the flask to be supported in position. The outer end of each of the posts 22 is provided with a hook member 23 which is pivotally secured thereto and provided with a handle member 24 which is of considerable weight. The flask is supported in position on the faces of the member 13, as illustrated by dotted lines in Figure 4, in the same manner as is customary in devices of this kind, with the pattern member adjacent to the face, while the flask surrounds the pattern and is provided with a base member, all of which are secured in position by means of a bar 25. The bar 25 is of a length slightly greater than the distance between the posts in either of the faces, and is designed to secure the said members in position by being placed over the base member and passed under the hooks 23. The weight of the members 24 will secure the hooks in position until the flask has been revolved to an inverted position, after which it will be released as hereinafter described.

The manner in which this flask is mounted; and the manner in which the patterns and base member are secured in position, is common to all machines of this kind, and for that reason a detailed description is omitted. The important feature in this connection is to provide means for moving the bottom part of the mold toward the pattern member after the sand has been placed in position. This should be done with a very steady, uniform and even pressure, which movement may be comparatively rapid at first and the speed of which should be reduced with an increased pressure at the same time. This I have accomplished by the following mechanism:

Secured to one side of one of the members 12 I have provided a boss or bracket 26, which is designed to receive a vertical shaft 27, the lower end of which is mounted in a projection 28 of the base member 10. Pivotally mounted on the shaft 27 is a swinging bracket member 29. This bracket member is provided with side members 30 and web members 31. All of these members are cast integral.

I have thus provided an open framework which is constructed very rigid but at the same time comparatively light, the said framework being provided with an opening 32 for the purpose of permitting mechanism to pass upwardly through said frame for the purpose of elevating the mold supporting platform 33.

This platform 33 comprises preferably two members 34 and 35, which are secured together by means of cross pieces 36. The

member 35 is provided with extensions 37 which are formed with a guide member 38 at each end. Each of these guide members 38 is designed to coact with guide flanges 39 on the inner faces of the uprights 12 when the platform 33 is being elevated. The flanges 39, however, are so arranged on the supports 12 that the platform 33 may swing in a horizontal plane when in position on the bracket 29. The platform 33 is held in position on the bracket 29 by means of lugs 40 which are designed to engage the faces of the members 30 to prevent movement of the bracket in other than a vertical or lifting direction. Each of the members 34 and 35 has its inner edge provided with downwardly extended flanges 41 and 42 respectively. Each of the flanges 41 and 42 is provided with a smooth edge designed to be engaged by rollers, as hereinafter described.

For elevating the platform 33 I have provided the following mechanism:

Secured to the back side of the base member 10 I have provided a vertical frame 43 having braces 44 and a horizontal lever supporting member 45. Secured to the bracket 43 by means of a suitable bracket 46 is an air cylinder 47. This cylinder is provided at each end with a head 48 and a slideable piston 49. The lower head member 48 is provided with a packing gland 50 designed to receive a piston rod 51, the upper end of which is operatively connected with the piston 49. The lower head 48 is provided with an air pipe 52, while the upper head 48 is provided with an air pipe 53. Both of the pipes 52 and 53 are in communication with a valve block 54. This block 54 is provided with a valve 55 having ports 56, 57, 58, 59 and 60. The block 54 is also provided with ports 61 and 62 which are in communication with the atmosphere, and the port 62 being provided with a set screw 63, the purpose of which will hereinafter be made clear. An air supply pipe 64 is provided and is in communication with the block 54.

Mounted on the base 10 are rock shafts 65, parallel to each other and parallel to the top of the platform 33. The back end of each of the rock shafts 65 is provided with an inwardly extending arm 66, the inner end of each being provided with a link 67, the free end of which is connected to a cross head 68, the cross head 68 being mounted on the lower end of the piston rod 51. The cross head 68 is designed to travel in a guide member 69.

Near the forward end of each of the rock shafts 65 and centrally beneath the platform 33 and beneath the center of the frame 14, I have provided an arm 70, each of which is provided with a T-head 71, each end of which is provided with a roller 72. The rollers 72 are spaced apart a distance equal to the distance of the flanges 41 and 42, and

so arranged as to be engaged by said flanges when the platform 33 is in its normal position. The rollers 72 are so spaced apart that they will engage the flanges 41 and 42 5 at a point a distance from each end equal to substantially one-third of the length of the said flanges.

The pattern frame 13 is provided with a rapping device 72^a, which is of the compressed air type and of the ordinary construction, said rapping device being in communication with a supply pipe 64 by means of a pipe 73 which extends centrally through one of the pivot members 15 and is in communication with one end of the hose 74. The opposite end of the hose 74 is in communication with a valve block 75 which is provided with a valve 76, the valve block 75 being in communication with the pipe 64 10 by means of a pipe 77 and a T 78. The valve 76 is provided with a stem 79 which is operatively connected with a rod 80, one end of which is provided with an arm 81 having an operating rod 82. The valve 55 20 is provided with a stem 83 which is operatively connected to one end of a rod 84 having a rock arm 85 connected to a hand operated rod 86. The shafts 80 and 84 are supported by means of the bracket member 30 45, while the rods 82 and 86 are supported in a horizontal position by means of a bracket 86^a on top of one of the members 12.

The operation of my improved molding machine is as follows: 25 Assuming that the air supply pipe 64 is in communication with a suitable supply tank, and that the various movable mechanisms of the device are in normal position, that is with the pattern frame 13 having its pattern supporting faces horizontal, with the latch 16 in position in the notch 21, and the piston 49 at its lower limit of movement in the cylinder 47, this will leave the rollers 72 in the position illustrated in Figure 1 40 of the drawings, with the centers of the rollers and the centers of the shaft in a horizontal plane. When the rollers 72 are in this position the bracket 29 may be moved to a position directly over said rollers, the 45 movement of which is limited by means of a lug 87 extending downwardly from said bracket and designed to engage a lug 88 extending upwardly from the frame 10. The platform 33 will then be in position on said bracket 29, with its flanges 41 and 42 immediately over the rollers 72, as clearly illustrated in Figure 4. The arms 66 will also be in a horizontal position and parallel to the arms 70. The links 67 will extend downwardly, as shown in dotted lines in Figure 1, to substantially a vertical position, and the valve 55 will be moved to a closed position.

A pattern board 89 will then be placed 65 on the top of the member 13 and secured

in position thereon by means of suitable pins. A flask 90 will then be placed in position and filled with sand. The bottom board 91 will be placed in position bottom side up, and the bar 25 placed above said bottom member and under the hooks 23, the weighted ends 24 holding the hooks 23 in position.

The upper member of the flask may be placed on the opposite side of the member 75 13 in the same manner. A description of the operation of one, however, will be sufficient.

The pattern frame 13 will be rotated after releasing the catch 16, until the flask 90 is 80 on the under side, the said flask being held in position by means of the bar 25 and the hooks 23. There will be a slight distance between the upper face of the platform 33 and the bottom board 91.

The hand rod 86 will then be grasped and moved to the rear, which will cause the valve 55 to assume the position shown in Figure 7 of the drawings, with the port 57 in communication with the supply pipe, the port 90 56 in communication with the pipe 52, the port 58 in communication with the pipe 53, and the port 59 in communication with the port 61. Air will then pass from the supply pipe 64 through the pipe 52 to the 95 bottom side of the piston 49, which will then be elevated. The air in the upper end of the cylinder 47 will be exhausted through the pipe 53 and the port 61. This, through the piston rod 51, will cause the cross head 100 68 to be elevated, which in turn will cause the shafts 65 to be oscillated, which in turn will cause the rollers 72 to engage the bottom sides of the flanges 42 and 41 and the said flanges to be elevated, which in turn 105 will cause the platform 33 to be elevated until it engages the bottom of the board 91, which will be forced up into the flask, causing the molding material to be compressed and packed around the pattern. The tension on the bar 25 will also be released, which 110 will permit the hooks 23 to disengage said bar, due to the weight of the members 24, thereby providing automatic means for releasing the said bar and disconnecting the 115 flask and the frame 13.

As the rollers 72 are elevated their supporting arms will approach a vertical position, shown in Figure 6, and the links 67 will approach a horizontal position, as 120 shown in said figure. This will produce a compound lever effect, which will cause the flask to be elevated comparatively rapidly at first, but the speed of which will be gradually reduced and the power as applied to the said platform, increased. This provides for uniform movement of the piston 49, which may be constructed of a comparatively small diameter but which will produce a very effective and steady lifting and 125 130

compressing power at the extreme end of the stroke without increasing the pressure in the cylinder.

After the platform 33 has been moved to its upward limit of movement and the proper pressure applied to the material within the mold, (this variation of pressure may be accomplished by varying the thickness of the bottom plate 91, and after this has been once adjusted it is not necessary to readjust it) the hand rod 86 will then be again actuated and the valve 55 moved to the position shown in Figure 8, with the port 56 in communication with the pipe 64, the port 57 in communication with the pipe 53, the port 58 in communication with the port 62, and the port 60 in communication with the pipe 52. This will permit air to enter the upper end of the cylinder 47 above the piston 49, which piston will start to move downwardly, the downward movement, however, being limited by the exhaust air which will then pass out through the pipe 52 and through the port 62, said port being restricted by means of the set screw 63. The downward movement of the piston 49 can thus be regulated by adjusting the screw 63. The hand rod 82 will then be operated, causing the valve 76 to be opened in communication with the flexible pipe 74, which will then cause the ragger 72^a to be operated as the platform 33 starts to descend, but the movement of the said platform will be very slow at first, due to the restriction of the passage 62 and also due to the slow movement of the rollers 72, the said rollers being moved very slowly on account of the compound link movement above described. This variable movement from a slow speed to a higher speed, and vice versa, I shall term in the claims an "accelerated movement" or "accelerated speed," for the sake of convenience.

It will thus be seen that I have provided means whereby the sand will be very slowly and steadily pulled from the pattern on the first part of its stroke, which will give the ragger sufficient time to loosen all portions of the pattern before portions of the sand become broken loose from the molds.

After the flask has reached its downward limit of movement, which will leave the patterns secured to the member 13 and the flask resting on the platform 33 with the guide members 38 below the ends of the flanges 39, the bracket 29 may be swung in a horizontal plane until the flask is moved to a position from under the pattern frame 13, at which time it may be easily grasped by the operator and lifted and carried to any desired position in the molding room.

In my copending application before identified, the bracket member 29 is designed to be elevated with the flask, while in my present application the platform 33 is elevated with the flask and the bracket 29

rests stationary. This has a marked advantage over my former device, due to the fact that in said former device the flask supporting member was pivotally and slidably mounted on a shaft. I experienced considerable difficulty in keeping this shaft properly lubricated, due to the fact that the fine sand would collect on the shaft, thereby causing it to wear very rapidly and also bind, which prevented free and easy movement which is accomplished in my present device.

I also have provided an improved means for locking the flask to the pattern frame, which eliminates the crooked bail and also a more or less complicated latch device which was likely to get out of order.

The main frame has been considerably simplified and the device provided with three wheels in place of four, which makes the device very stable even if it is supported on a floor having an uneven surface.

The whole mechanism is formed in a unit having all of its parts rigidly and securely mounted on a rigid base which may be easily and quickly moved from one position to another, or moved out of the way when not in use.

I claim as my invention:

1. In a molding machine, a main frame, a pattern frame mounted on said main frame, a mold table, an air actuated device, and means operated by said air actuated device for imparting an accelerated movement to said mold table to move it to or from said platform.

2. In a molding machine, a main frame, a pattern frame mounted on said main frame, a mold table, an air cylinder, a piston, and a compound lever device operatively connected with said piston for elevating and lowering said mold table at an accelerated speed when the said piston is operated at a substantially uniform speed.

3. In a molding machine, a main frame, a pattern frame mounted on said main frame, a mold table, an air cylinder, a piston, a compound lever device operatively connected with said piston for elevating and lowering said mold table at an accelerated speed when the said piston is operated at a substantially uniform speed, and means for controlling the speed of said piston.

4. In a molding machine, a main frame, a pattern frame mounted on said main frame, a supporting bracket pivoted to said main frame to swing horizontally, a mold table detachably mounted on said bracket, an air cylinder, a piston, and a compound lever device operatively connected with said piston for elevating and lowering said mold table at an accelerated speed when the said piston is operated at substantially a uniform speed.

5. In a molding machine, a main frame,

- a pattern frame mounted on said main frame, a supporting bracket pivoted to said main frame to swing horizontally, a mold table detachably mounted on said bracket, 5 an air cylinder, a piston, a compound lever device operatively connected with said piston for elevating and lowering said mold table at an accelerated speed when the said piston is operated at substantially a uniform 10 speed in one direction, and adjustable and automatic means for controlling the said piston in the opposite direction.
6. In a molding machine, a main frame having guide flanges, a pattern frame 15 mounted on said main frame, a mold table, said table having guide devices designed to coat with said guide flanges when the said table is elevated, and means for elevating said table, comprising an air cylinder, a piston, 20 and a compound lever device operatively connected with said piston, the said lever device being designed to elevate and lower said mold table at an accelerated speed.
7. In a molding machine, a main frame, 25 a pattern frame mounted on said main frame, a mold table, and means for moving the mold table toward said pattern frame, comprising a reciprocating power member arranged perpendicular relative to the mold 30 table, means for controlling the movement of said power member, a set of rock shafts mounted parallel to each other and parallel to said mold table, an inwardly projecting arm for each of said rock shafts, adjacent 35 to one side of said platform, said arms be- ing substantially parallel with the said table when in one position of its movement, and perpendicular thereto when in another position of its movement, rollers carried by the free end of said arms for elevating said 40 platform, an actuating arm for each shaft substantially in the same plane as said first arms, and links for operatively connecting the said power member and said actuating arms, the said links being designed to rest 45 substantially parallel with the power member when in the first position of their movement, and perpendicular thereto when in their second position of movement.
8. In a molding machine, a main frame, 50 a pattern holding frame mounted on the upper portion of the main frame for rotation, a mold table below said pattern frame, means for raising and lowering said mold table, and means for locking a mold flask 55 having a movable bottom member, to said pattern holding frame, comprising adjustable posts mounted perpendicular in the face of said frame, a pivoted hook on each post, and a flask supporting bar, the hooks 60 being provided with weighted end members so that said hooks will lock the flask through the pattern holding frame when the flask is in an inverted position above the pattern holding frame, and automatically unlock 65 the flask when in an upright position beneath the pattern frame and pressure is applied to the bottom member of said flask.

FRANZ J. WOOD.
